[57] CLAIM

The ornamental design for a combined clipboard and
adjustable support therefor, as shown and described.

DESCRIPTION

FIG. 1 is a top, left front perspective view of a
combined clipboard and adjustable support therefor showing
my new design;

FIG. 2 is a front elevational view drawn to an enlarged
scale;

FIG. 3 is a rear elevational view of FIG. 2;

FIG. 4 is a top plan view of FIG. 2;

FIG. 5 is a bottom plan view of FIG. 2, with the
clipboard member removed for convenience of illustration;
and

FIG. 6 is a left side elevational view of FIG. 2, the right
side being a mirror image thereof.

FIG. 1

FIG. 2

FIG. 3

FIG. 4

FIG. 5

FIG. 6
